DESIGN FOR A MICROSCOPE LAMP

Gustav F. Spindler, San Francisco, Calif.

Application February 23, 1937, Serial No. 67,782

Term of patent 7 years

To all whom it may concern:

Be it known that I, Gustav F. Spindler, a citizen of the United States of America, residing at San Francisco, in the county of San Francisco and State of California, have invented a new, original, and ornamental Design for a Microscope Lamp, of which the following is a specification, reference being had to the accompanying drawing, forming a part thereof.

Fig. 1 is a front elevation of the microscope lamp, showing my new design;

Fig. 2 is a side elevation thereof; and
Fig. 3 is a top plan view thereof.

I claim:—

The ornamental design for a microscope lamp substantially as shown.

GUSTAV F. SPINDLER.
